UNITED STATES PATENT OFFICE.

FELIX A. MOODY, OF HAHIRA, GEORGIA.

POWDER DUSTER.

Application filed June 12, 1923. Serial No. 644,946.

To all whom it may concern:

Be it known that I, FELIX A. MOODY, a citizen of the United States, residing at Hahira, in the county of Lowndes and State 5 of Georgia, have invented a new and useful Powder Duster, of which the following is a specification.

This invention has reference to a device especially designed for use in distributing 10 poisonous powder employed for exterminating insects that usually infest vegetation.

The primary object of the invention is to provide a device of this character which will discharge a predetermined quantity of 15 powder, novel means being provided for regulating the quantity of material discharged.

Another important object of the invention is to provide means that may be held in a 20 position in proximity to the infested plant to insure against the wind blowing the powder from the plant, when the powder is being discharged from the container.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed, may be made within the scope of what is claimed, without departing from the spirit of the invention.

35 Referring to the drawings:

Figure 1 is a side elevational view of a powder distributing device constructed in accordance with the invention;

Figure 2 is a side elevational view 40 closing the opposite side of the device;

Figure 3 is a sectional view taken on line 3-3 of Figure 1;

Figure 4 is a detail view disclosing the upper portion of the container;

45 Figure 5 is an enlarged fragmental view disclosing the guide for the movable rod employed for jarring the container;

Figure 6 is an enlarged detail view 50 disclosing the adjusting means for the removable rod.

Referring to the drawings in detail, the reference character 5 designates the container which may be of any desired shape and size, however in the present showing the

55 preferred form is circular in cross section. Openings 6 are formed in the bottom of the

container 5, through which openings the powder to be distributed passes. Secured to the container and extending upwardly therefrom, is a frame 7 that includes the 60 cross bar 8 formed with an opening 9, disposed intermediate the ends of the bar 8, which opening accommodates the vertically movable agitating rod 10.

At the lower end of the rod 10 is a nut 11 65 operating on the threaded portion 12 thereof, the nut providing a support for the coiled spring 13 that has one end thereof engaging the upper surface of the nut as clearly shown by Figure 4 of the drawings. 70 The upper extremity of the coiled spring 13 engages the under surface of the bar 8 to cushion the movement of the container when the same has been released by the tripping mechanism to be hereinafter more fully 75 described.

Positioned on the lower end of the rod 10 is an arm 14 that extends laterally therefrom, and may, by movement of the nut 11 be adjusted longitudinally of the rod 10 to 80 tension the coiled spring 15, that has one end thereof secured to the outer extremity of the arm 14.

A bracket 16 is secured to the frame 7 and has a right angled upper extremity 17 85 formed with an opening to receive the eye bolt 18 on which operates the winged nut 19 to adjust the bolt 18 with respect to the bracket 16, the upper end of the coiled spring 15 being secured to the eye bolt 18. 90

The upper end of the rod 10 is offset at 20 from where the same extends upwardly providing a section 21 terminating in a right angled portion 22, providing a handle, by means of which the device may be supported 95 by the operator.

Extending laterally from the frame 7 is a yoke indicated at 23 into which the lower end of the trip 24 extends, the upper edge of the trip bar being supplied with a roller 100 25. The trip bar is held in spaced relation with the rod 16, by means of the arm 26 which is formed with a slotted portion 27 designed to receive the bolt 28 supplied with a wing nut 29 so that the angle at which the trip bar 24 operates, may be adjusted to cause the device to be operated under varying spring pressures, thereby regulating the quantity of material being discharged from the container. 105

Connected with the lower end of the trip bar 24 is an operating bar 30 which has its 110

upper extremity pivotally connected with the movable bar 31 that has pivotal connection with the upwardly extended portion 21 at 32, the opposite end thereof being forked 5 at 33, which forked portion accommodates a guide rod 34 that depends from the handle portion 22. The lower end of the rod 34 is threaded as at 35 to accommodate the winged nut 36 which engages the movable 10 bearing member 37 which in turn engages the under surface of the forked extremity 33 to move the bar 31 vertically, and adjust the tension of the spring 38 that is shown as connecting the bar 31 to the operating bar 15 30. The bar 31 may be supplied with a handle portion 39 which may be of rubber or other suitable material to prevent injury to the operator's hand while the device is in use.

20 Formed on the inner edge of the bar 30 are teeth 40 that engage under the upper bar 41 of the frame 7 causing the rod 10 to move downwardly when the movable bar 31 is moved upwardly by the operator's 25 fingers, the roller 25 at the upper end of the trip 24 contacting with the lower extremity of the section 21 which in turn moves the lower extremity of the trip 24 disengaging the teeth 40 from the upper 30 bar 41 of the frame.

It is obvious that as the rod 10 moves downwardly, the spring 15 is placed under tension, and when the teeth 40 are disengaged from the bar 41, the coiled spring 35 15 returns the rod 10 to its normal position, causing a sudden jar of the container to the end that material held in the container will be shaken therefrom.

It might be further stated that in order 40 to securely hold the device, a handle 42 is provided, which may be grasped by the left hand of the operator while the right hand is operating the bar 31 in a manner as described.

45 I claim:—

1. In a device of the character described, a container, a vertical movable rod having connection with the container, means associated with the rod and container for 50 holding the container stationary while the rod is being moved, and said container holding means adapted to automatically release the container, to permit the container to move over the rod, and means on the rod 55 for restricting movement of the container.

2. In a device of the character described, a container, a rod supported above the container and movable with respect thereto, means associated with the rod for holding 60 the container while the rod moves with respect thereto, and said container holding means adapted to operate automatically to release the container, and resilient means for automatically moving the container to its 65 initial position.

3. In a device of the character described, a container having discharge openings therein, a vertically movable rod connected with the container and having a right angled upper end providing a handle, an operating 70 bar associated with the rod, a trip bar having pivotal connection with the lower end of the operating bar and adapted to operate to restrict movement of the container with respect to the rod, and said trip bar 75 adapted to automatically release the container to permit the same to move over the rod.

4. In a device of the character described, a container, a rod supporting the container and movable with respect thereto, an operating bar disposed adjacent to the rod and adapted to move with respect thereto, a trip bar pivotally connected to the operating bar at a point adjacent to the lower end 80 thereof, said trip bar extending at an angle with respect to the operating bar, means for permitting of an adjustment of a trip bar laterally, and said trip bar adapted to engage the rod to release the container, and means for moving the container with respect to the rod.

5. In a device of the character described, a container having discharge openings formed therein, a frame supported by the 95 container and disposed thereabove, a rod extending through the frame and having a handle at its upper end, an operating bar associated with the rod and having teeth, said teeth adapted to engage the frame to restrict movement of the container with respect to the rod, when the rod moves downwardly, a trip bar having connection with the operating bar, and adapted to move into engagement with the upper portion of 100 the rod to automatically disconnect the teeth from the frame, and resilient means for causing the container to move over the rod.

6. In a device of the character described, a container, a frame supported above the 110 container and having connection therewith, a rod extending through the frame, a bar disposed adjacent to the open end of the container and through which the rod extends, a coiled spring at the lower end 115 of the rod and adapted to engage under the bar, said rod adapted to move downwardly, an operating bar associated with the rod, means carried by the operating bar, and engaging the frame for restricting movement of the container with respect to the rod, and means for automatically releasing the container.

7. In a device of the character described, a container, a frame secured to the container and extending upwardly therefrom, a rod extending through the frame and having an offset portion, the lower end of the rod extending to a point within the container and carrying a spring, an operating 125 130

- bar movable with respect to the rod and having teeth engaging the frame, to restrict movement of the container while the rod is being moved, a trip bar carried by the operating bar and adapted to move into engagement with the offset portion of the rod to disengage the teeth and frame, and means for returning the container to its initial position.
- 10 8. In a device of the character described, a container, a frame extending upwardly from the container, a rod extending through the frame and having a handle formed at one end thereof, a movable bar pivotally connected with the rod, an operating bar having connection with the movable bar, the movable bar lying in proximity to the handle to be gripped by the operator, to move the operating bar, said operating bar adapted to engage the frame to temporarily restrict movement of the container with respect to the rod, and adjustable means for disengaging the operating bar and frame to allow the container to move over the rod.
- 15 In testimony that I claim foregoing as my own, I have hereto affixed my signature in the presence of two witnesses.

FELIX A. MOODY.
